INTERNAL-COMBUSTION ENGINE

Application filed February 4, 1928. Serial No. 251,789.

This invention relates to internal combustion engines and methods of operating such engines and has among its objects the provision of means and methods for improving the general performance of the engine.

In engines of the hydrocarbon type it is common practice to employ a carburetor or other mixing device for vaporizing the hydrocarbon with air, the fuel mixture being then conducted to the engine cylinders for combustion. It has been determined that a certain portion of the hydrocarbon is carried along with the fuel mixture in liquid form, not being vaporized by the carburetor. Such a condition is generally prevalent with the present day fuels commonly used for internal combustion engines, and is particularly pronounced in starting an engine as in cold weather or after the engine has been idle for a sufficient length of time to have cooled relative to its normal operating temperature. At such times, and also to a lesser extent during the normal operation of the engine, the wet fuel particles including condensed portions of the fuel mixture tend to collect in the conduit intermediate the carburetor and cylinders, resulting in a sluggish action of the engine, difficulty in starting and a generally undesirable engine performance.

My invention in its broad aspects is applicable to any type of hydrocarbon engine of the carbureted fuel mixture type. I have provided means and methods for removing the wet fuel particles from the fuel mixture conduit at any suitable point or points. This may be done in several ways although I prefer for simplicity and convenience to collect the wet fuel particles and preferably to remove the collected wet fuel particles by suction. Thus I may remove the wet fuel particles by suction derived by the engine piston, the wet particles being conducted from the fuel mixture supply conduit to a point of disposal, preferably into the cylinder separately from the supply conduit. By such a general method and engine construction I have greatly improved the starting ability of the engine as well as overcoming the sluggish action of the engine.

One important application of my invention relates to sleeve valve and like types of engines. This general type of engine is especially susceptible to the difficulties and objections aforesaid and I have obtained greatly improved results in sleeve valve engines embodying my invention. I have illustrated my invention in connection with a typical well known type of engine known as the "Burt-McCollum" engine in which a single sleeve valve associated with each cylinder has a combined reciprocating and oscillating movement, although as aforesaid my invention is also applicable to other types of sleeve valve engines as well as poppet valve and other types of engines, and it is not my purpose to limit the scope of my invention except as specifically recited in the appended claims.

In the accompanying drawings in which like reference characters indicate corresponding parts,

Fig. 1 is a sectional elevation view through a cylinder of the engine,

Fig. 2 is a plan sectional view through the engine at the cylinder ports,

Fig. 3 is a side elevation view of the intake manifold and associated parts, and

Fig. 4 is a diagrammatic view illustrating the porting action of the sleeve valve with the cylinder.

Referring to the drawings, reference character 10 illustrates the engine cylinder block having cylinders 11 jacketed at 12 for circulation of a cooling fluid. Each cylinder 13 may be closed by a cylinder head 13 spaced within the cylinder to accommodate the movement of one or more sleeve valves 14. The sleeve valve in the illustrated embodiment of my invention is positioned between the cylinder and piston 15, the latter operating the usual connecting rod 16 and engine crankshaft 17.

Each cylinder 11 has intake and exhaust ports 18, 19 respectively opening into intake and exhaust cylinder chambers 20, 21. These chambers are divided by walls 22 between adjacent cylinders and have upper and lower floors 23, 24 respectively whereby the intake mixture and exhaust gases are confined. The

intake chambers 20 communicate at the cylinder block openings 25 with a fuel mixture supply manifold 26. The hydrocarbon, such as commercial gasoline, is carbureted by a usual or other suitable mixing device or carburetor illustrated at 27. The exhaust chambers 21 communicate at the cylinder block openings 28 with the exhaust manifold 29.

10 The sleeve valve 14 has intake and exhaust ports 30, 31 respectively, and for the type of engine illustrated any point on the sleeve is moved in a closed curve path 32 with respect to the cylinder wall whereby the usual 15 valving functions of the engine take place. Any suitable mechanism for imparting the desired movement to the sleeve valves may be employed, that illustrated comprising the well known layshaft 33 driven at half crank-shaft 20 angular velocity for the illustrated four stroke cycle engine. The layshaft has a crank 34 connecting and driving each sleeve valve by a link 35 pivotally connected at 36 with the sleeve and having a bearing 37 on the 25 crank 34. Further details of the driving mechanism are deemed unnecessary for the present description of my invention since this and other suitable sleeve driving mechanisms are generally well known in the art.

30 In order to collect or concentrate the unvaporized and condensed particles of hydrocarbon and fuel mixture passing from the carburetor 27 to the intake ports 18, I have inclined the intake chamber floor 24 downward- 35 ly and outwardly, preferably from the ports 18 to the cylinder openings 25. Any wet particles tending to form or collect in this portion of the fuel mixture supply conduit will therefor pass by gravity action outwardly

40 from the ports 18 to the opening 25. The wet particles or portions of the hydrocarbon and fuel mixture are collected in one or more traps or conduits 38, preferably having communication through branch conduits 39 at each

45 cylinder with cylinder openings or ports 40. Each sleeve valve has a port or auxiliary opening 41 suitably located for cooperation with the cylinder opening 40 as illustrated in Fig. 4. In the position of the ports 30, 31

50 illustrated in this figure the intake ports 30 are in communication with the cylinder intake ports 18, the sleeve and cylinder exhaust ports 32, 19 respectively being out of registration. The engine is thus completing its intake cycle, the piston 15 moving downwardly and the sleeve valve moving generally upwardly as indicated by the arrows in Fig. 1.

At this point in the cycle, as illustrated in Figs. 1 and 4, the piston 15 uncovers the sleeve 60 auxiliary port 41 and the latter port moves into registration with the cylinder opening 40, thus inducing a suction, for at least a portion of the intake cycle, in the conduit 39 from the cylinder. As the piston 15 completes its intake stroke the port 41 moves out

of registration with the cylinder opening 40 as at 41' and is free from communication with opening 40 throughout the remaining cyclical events. The angle 42 of registration of ports 40, 41 may be varied according to the desired 70 degree of suction and length of time for the suction in conduit 39. Thus, for example, the relative sizes of these ports and their position with respect to the intake cycle of the main sleeve and cylinder ports may be varied 75 as desired. In Fig. 4 the sleeve intake and exhaust ports 30, 31, respectively represent the sleeve ports 30, 31 when the sleeve has just completed its exhaust cycle, intake about to take place.

By reason of my invention the wet fuel particles are removed from the fuel intake system between the carburetor and cylinder intake ports as fast as they accumulate. Any wet particles collecting between successive intake strokes for any cylinder will build up in the conduits 39, 38 and will be removed at the next suction stroke. The relatively small capacity of the conduit 39 with respect to the intake manifold 26 is not sufficient to interfere with the normal functioning of the engine intake.

I prefer to provide a conduit 39 for each cylinder in order to obtain the same conditions of operation for each engine cylinder 85 although if desired the headers 38 may communicate with one or any number of the cylinders, or the conduits 39 may extend to other suitable points for final disposal of the wet particles removed from the intake system.

Other suction means within the teachings of my invention may be employed for removing the wet fuel particles from the intake conducting system, as desired. Other adaptations and modifications of my invention will 105 readily suggest themselves from the teachings of my invention and I do not intend to limit the scope of my invention except as specifically recited in the following claims.

What I claim as my invention is:

1. In an internal combustion engine, a cylinder, a piston, fuel mixture conducting means for the cylinder, and means independent of the fuel mixture conducting means for positively removing unvaporized portions of 115 said fuel mixture from said conducting means.

2. In an internal combustion engine, a cylinder, a piston, fuel mixture conducting means for the cylinder, a conduit communicating with said fuel mixture conducting means, and means separate from said fuel mixture conducting means for producing a suction in said conduit.

3. In an internal combustion engine, a conduit for supplying a vaporized hydrocarbon to the engine cylinder, and a second conduit communicating with the first said conduit for removing therefrom unvaporized portions 125 of the hydrocarbon, said second conduit also 130

- communicating with the cylinder independently of the first said conduit.
4. In an internal combustion engine, a main conduit for supplying a vaporized hydrocarbon to the engine, an auxiliary conduit communicating with the main conduit, and suction means for the auxiliary conduit for removing unvaporized hydrocarbon from the main conduit, said suction means being independent of the main conduit. 5. In an internal combustion engine, an intake system for supplying a vaporized hydrocarbon to the engine, a second conduit communicating with the first said conduit, and means utilizing the engine suction independently of the intake system for removing unvaporized hydrocarbon from the intake system through the second said conduit. 10. 6. In an internal combustion engine, a conduit for supplying a vaporized hydrocarbon to the engine, and a second conduit communicating with the first said conduit for removing therefrom unvaporized portions of the hydrocarbon, said second conduit communicating with a cylinder of the engine independently of the first conduit. 15. 7. In an internal combustion engine, a cylinder, a conduit for supplying a vaporized hydrocarbon to the engine cylinder, a second conduit communicating with the first said conduit for removing therefrom unvaporized portions of the hydrocarbon, said second conduit communicating with the engine cylinder, and a valve controlling said second conduit. 20. 8. In an internal combustion engine, a cylinder, an intake system for supplying a vaporized hydrocarbon to the engine cylinder, a conduit communicating with the intake system for removing therefrom unvaporized portions of the hydrocarbon, said conduit opening into the cylinder, and a valve controlling said second conduit. 25. 9. In an internal combustion engine, a cylinder, a piston, fuel mixture conducting means for the cylinder, separate means for removing unvaporized portions of said fuel mixture from said conducting means, and a common valve controlling mechanism for both of said means. 30. 10. In an internal combustion engine, a cylinder, a piston, sleeve valve means associated with the cylinder and piston, fuel mixture conducting means for passing substantially the entire supply of fuel mixture to the cylinder controlled by said sleeve valve means, and means controlled by said sleeve valve means for removing unvaporized portions of said fuel mixture from said fuel mixture conducting means, said last means including an auxiliary conduit for passing the said unvaporized portions of the fuel mixture into the cylinder. 35. 11. In an internal combustion engine, a cylinder, a piston, a single sleeve valve having a combined reciprocating and oscillating
- movement, said cylinder and sleeve having cooperating intake and exhaust ports, fuel mixture supply means for passing substantially the entire supply of fuel mixture to the cylinder, said sleeve and cylinder having auxiliary cooperating ports, and fuel mixture conducting means between the auxiliary cylinder port and the fuel mixture supply means. 40. 12. In an internal combustion engine, a cylinder, a piston, a single sleeve valve having a combined reciprocating and oscillating movement, said cylinder and sleeve having cooperating intake and exhaust ports, fuel mixture supply means for passing substantially the entire supply of fuel mixture to the cylinder, said sleeve and cylinder having auxiliary cooperating ports, and fuel mixture conducting means between the auxiliary cylinder port and the fuel mixture supply means, said auxiliary ports being positioned on the sleeve and cylinder respectively so that they are in registration during at least a portion of the intake stroke of the piston thereby producing a suction in the said fuel mixture conducting means to remove therefrom unvaporized portions of the fuel mixture. 45. 13. In an internal combustion engine, a cylinder, a piston, fuel mixture supply means for passing substantially the entire supply of fuel mixture to the cylinder, valve controlled means establishing communication between the cylinder and fuel mixture supply means during the intake stroke of the piston, and valve controlled means including a conduit opening into the cylinder during at least a part of said piston intake stroke for removing unvaporized portions of the fuel mixture from the fuel mixture supply means. 50. 14. In an internal combustion engine of the sleeve valve type, a cylinder having an intake port substantially in the longitudinal plane of the engine containing the cylinder axis, sleeve valve means associated with the cylinder and ported for cooperation with said cylinder port, an intake chamber surrounding a portion of the cylinder in the vicinity of said cylinder port, said chamber having a floor sloping downwardly and outwardly from said cylinder port for draining unvaporized particles of fuel intake mixture, and means supplying fuel intake mixture to said intake chamber. 55. 15. In an engine of the sleeve valve type, a cylinder block having a cylinder formed with a plurality of intake ports located inwardly of the cylinder block substantially in the longitudinal plane of the engine containing the cylinder axis, an intake chamber in the cylinder block open to said cylinder ports and provided with a floor sloping downwardly and outwardly from said cylinder ports to one side of the cylinder block, and fuel mixture supply means for the intake chamber. 60. 16. In an engine of the sleeve valve type,

a cylinder block having a cylinder formed with a plurality of intake ports substantially in the central longitudinal plane of the engine, an intake chamber in the cylinder block 5 open to said cylinder ports, and provided with a floor sloping downwardly and outwardly from said cylinder ports to one side of the cylinder block, fuel mixture supply means for the intake chamber, and a conduit 10 positioned to receive unvaporized portions of the fuel mixture drained by said intake chamber floor.

17. In an engine of the sleeve valve type, a cylinder block having a cylinder formed 15 with a plurality of intake ports substantially in the longitudinal central plane of the engine, an intake chamber in the cylinder block open to said cylinder ports and provided with a floor sloping downwardly and outwardly 20 from said cylinder ports to one side of the cylinder block, fuel mixture supply means for the intake chamber, and means inducing a suction in said conduit.

18. In an internal combustion engine, a 25 cylinder, a piston, sleeve valve means concentric with the cylinder, said cylinder having main intake and exhaust ports lying substantially in a common plane perpendicular to the axis of the cylinder, said sleeve valve 30 means provided with intake and exhaust ports respectively cooperating with said cylinder ports, intake and exhaust manifolding devices respectively supplying fuel mixture to and conducting exhaust gases from said 35 cylinder intake and exhaust ports, said cylinder having an auxiliary port below the said plane containing the main intake and exhaust ports, said sleeve valve means being additionally ported for cooperation with said auxiliary 40 cylinder port during at least a portion of the intake stroke of the engine, and a conduit between said intake manifolding device and said auxiliary cylinder port.

19. In an internal combustion engine, a 45 cylinder, a piston, sleeve valve means concentric with the cylinder, said cylinder having main intake and exhaust ports lying substantially in a common plane perpendicular to the axis of the cylinder, said sleeve valve 50 means provided with intake and exhaust ports respectively cooperating with said cylinder ports, intake and exhaust manifolding devices respectively supplying fuel mixture to and conducting exhaust gases from said 55 cylinder intake and exhaust ports, said cylinder having an auxiliary port below the said plane containing the main intake and exhaust ports, said sleeve valve means being additionally ported for cooperation with said auxiliary 60 cylinder port during at least a portion of the intake stroke of the engine, and a conduit between said intake manifolding device and said auxiliary cylinder port, said sleeve valve means having a combined reciprocating and oscillating movement.

20. In an internal combustion engine, a cylinder, a piston, sleeve valve means concentric with the cylinder, said cylinder having main intake and exhaust ports lying substantially in a common plane perpendicular to the axis of the cylinder, said sleeve valve means provided with intake and exhaust ports respectively cooperating with said cylinder ports, intake and exhaust manifolding devices respectively supplying fuel mixture and 70 to conducting exhaust gases from said cylinder intake and exhaust ports, said cylinder having an auxiliary port below the said plane containing the main intake and exhaust ports, said sleeve valve means being additionally 75 ported for cooperation with said auxiliary cylinder port during at least a portion of the intake stroke of the engine, and a conduit between said intake manifolding device and said auxiliary cylinder port, said conduit having a relatively small conducting capacity 80 compared with the conducting capacity of said intake manifolding device.

21. In an internal combustion engine, a 85 cylinder, a piston, sleeve valve means concentric with the cylinder, said cylinder having main intake and exhaust ports lying substantially in a common plane perpendicular to the axis of the cylinder, said sleeve valve means provided with intake and exhaust ports respectively cooperating with said cylinder ports, intake and exhaust manifolding devices respectively supplying fuel mixture to and conducting exhaust gases from said cylinder 90 intake and exhaust ports, said cylinder having an auxiliary port below the said plane containing the main intake and exhaust ports, said sleeve valve means being additionally 95 ported for cooperation with said auxiliary cylinder port during at least a portion of the intake stroke of the engine, and a conduit between said intake manifolding device and said auxiliary cylinder port, said conduit extending vertically downwardly from said intake manifolding device adjacent the side 100 wall of the engine.

22. In an internal combustion engine, a cylinder, a piston, sleeve valve means concentric with the cylinder, said cylinder having main intake and exhaust ports lying substantially in a common plane perpendicular to the axis of the cylinder, said sleeve valve means provided with intake and exhaust ports respectively cooperating with said cylinder ports, intake and exhaust manifolding devices respectively supplying fuel mixture and to conducting exhaust gases from said cylinder intake and exhaust ports, said cylinder having an auxiliary port below the said plane 110 containing the main intake and exhaust ports, said sleeve valve means being additionally ported for cooperation with said auxiliary cylinder port during at least a portion of the intake stroke of the engine, and a conduit 115 between said intake manifolding device and said auxiliary cylinder port, said conduit extending vertically downwardly from said intake manifolding device adjacent the side wall of the engine.

120

125

130

tween said intake manifolding device and said auxiliary cylinder port, said conduit having a relatively small conducting capacity to permit passage of unvaporized fuel particles but to restrict passage of vaporized fuel mixture for the most part to said intake manifolding device.

23. In an internal combustion engine, a piston, sleeve valve means concentric with the cylinder, said cylinder having main intake and exhaust ports lying substantially in a common plane perpendicular to the axis of the cylinder, said sleeve valve means provided with intake and exhaust ports respectively cooperating with said cylinder ports, intake and exhaust manifolding devices respectively supplying fuel mixture to and conducting exhaust gases from said cylinder intake and exhaust ports, said cylinder having an auxiliary port below the said plane containing the main intake and exhaust ports, said sleeve valve means being additionally ported for cooperation with said auxiliary cylinder port during at least a portion of the intake stroke of the engine, and a conduit between said intake manifolding device and said auxiliary cylinder port, said sleeve valve means comprising a single sleeve valve having a combined oscillating and reciprocating movement.

In witness whereof, I hereunto subscribe my name this 31st day of January, A. D. 1928.
OSCAR C. KREIS.
